REFRIGERATOR SHELF

Lyle W. Johnson, Minneapolis, Minn., assignor
to Gamble Stores Incorporated, Minneapolis,
Minn., a corporation of Delaware

Application April 27, 1937, Serial No. 139,141

2 Claims. (Cl. 211—152)

This invention relates to shelving structure for refrigerators and the primary object is to provide a refrigerator, otherwise of conventional design and of the type which is generally rectangular in cross section, with a shelf which includes a circular portion that is rotatable about a vertical axis so as to increase accessibility to articles within the refrigerator and permit maximum utilization of the storage space. A further object 5 is to provide a rotary shelf construction that is particularly designed for use in the rectangular type of box, thus utilizing the advantages which this design has over the cylindrical type, and without sacrificing shelf space at the areas where 10 the shelf structure does not permit of rotation. A further object is to provide a rectangular refrigerator shelf with a portion that is rotatable but which portion has its upper surface flush with the supporting surface of the remaining or adjacent shelf portion so that the shelf will have 15 as much unobstructed area as a plain shelf, and which condition will also permit articles to be moved or pushed horizontally onto and off of the movable part with respect to the stationary portion. A further object is to provide a refrigerator shelf with a rotary portion which occupies 20 a minimum amount of space, and is supported and designed in a novel, efficient, and practical manner. These and still other and more specific objects will be disclosed in the course of the 25 following specification reference being had to the accompanying drawings, wherein:

Fig. 1 is a cross sectional plan view through a refrigerator having a shelf construction embodying my invention.

Fig. 2 is a plan view of the shelf as shown in Fig. 1, but removed from the box, and with the 30 rotary portion of the shelf partly turned on its vertical axis, and having fragmentary portions broken away.

Fig. 3 is an enlarged detail plan view of a portion of the shelf, with various parts removed.

Fig. 4 is an enlarged end elevation of the shelf, 35 as seen from the left side in Fig. 1.

Fig. 5 is an enlarged section, on line 5—5 in Fig. 1.

Fig. 6 is a front edge elevation of the shelf.

Fig. 7 is an enlarged detail section on line 7—7 in Fig. 2.

Referring to the drawings more particularly and by reference characters 8 designates the side walls, 9 the back wall, and 10 the door of a refrigerator which may be of any suitable construction, and these parts are all insulated to pre-

clude or retard the transmission of heat as is well known in the art.

My improved shelf comprises a rigid rectangular frame 11, which is removably placed in the refrigerator, through the door opening, and is supported 5 by pegs 12 which project inwardly from the side walls 8 and are releasably engaged by fingers 13 and 14 at the ends of the frame, to hold the frame in proper position. The pegs 12 are preferably covered with small rubber sleeves so that the 10 fingers will frictionally and releasably retain the frame in proper position.

The frame further includes a circular wire ring 15, disposed at one side of the frame, and this ring is connected to the frame by varying lengths 16 of connecting bars or wires 16. Similar wires 17 connect the front and rear bars of the frame, at one side of the ring 15, and a cross bar 18 extends under the wires 17 to connect the ring 15 to the right hand side bar of the frame. A pair of 20 downwardly offset spaced bars 19 extend under and connect front and rear points of the ring 15 to support the rotatable shelf unit as will presently be described. All of the bars or wires 11, 15, 16, 17, 18 and 19 are spot welded, brazed, 25 or otherwise rigidly secured together at all points of contact so that they will be united in and comprise an integral rigid structure. It may here also be noted that the members 16 and 17 are all disposed in a common plane and are preferably of 30 flattened wire or strap metal bars, so as to present better supporting surface to the articles placed on the shelf. These members (16 and 17) are also preferably placed and secured over or on top of the parts 11, 15 and 18, and extend from front 35 to back so that articles may be freely and conveniently moved in and out, in sliding contact with the shelf, and without having obstructing contact with other parts of the structure.

The rotatable portion of the shelf comprises 40 a ring 20 across which extend parallel cross bars 21 of a character similar to members 16 and 17. The ring 20 is spaced concentrically within the ring 15 so as to have freedom for rotation therewithin, and is supported in such manner that 45 the supporting surface of the bars 21 will be horizontally flush with that of the bars 16 and 17.

The bars 21 which traverse the more central portion of the unit 20—21 extend over and are 50 secured to a rotatable disc or plate 22. This plate is supported by a somewhat similar coaxial plate 23, which, however, is stationary or non-rotatable and is carried by and secured to the support bars 19. The two plates are rotatably 55

connected or secured by a central pivot pin or bolt 24 which also extends through a spacer washer 25 between the plates.

The plate 23 is upwardly dished (Fig. 5) and has a peripheral flange which rests on and is secured to the bars 19. This plate is provided, near its outer edge, with an annular groove 26 in which rest ball bearings 27 that rotatably engage and support the plate 22. The ball bearings are retained in proper peripherally spaced positions by a flat retention ring 28, which is loosely disposed between the two plates 22 and 23 so that it can rotate freely with the balls about the axis of pin 24. The ring is preferably provided with a series of peripherally spaced bosses 29, one near each bearing hole and these bosses have for their purpose to retain the ring in proper operative position upon the surface of plate 23, without, however, interfering with the bearing 20 and supporting contact of the bearings with the under surface of plate 22.

The construction of the shelf, as above described, is such that the rotating portion is present and fully operative without in any way occupying appreciably more storage space than in a solid shelf; and the fact that the supporting surfaces of the rotating and stationary shelf portions are flush with each other is also a substantial advantage in that articles may be moved from one to the other without being lifted. Nor is the supporting space or area in any way more restricted than in a plain rectangular shelf as all parts of the shelf, even including the corner areas adjacent the rotary portion, are available and accessible for use in that capacity.

It is understood that suitable modifications may be made in the design and structure of the shelf, as herein disclosed, without departing from the spirit and scope of the appended claims.

Having now therefore fully shown and described my invention, what I claim to be new and desire to protect by Letters Patent is:

1. A refrigerator shelf comprising a reticu-

lated stationary frame having means presenting a horizontal supporting surface with a circular opening therein, a circular support mounted for rotation in said opening and having an upper surface disposed in a plane substantially flush with the supporting surface of the frame, a pair of superposed circular concentric members, the lower one carried by the frame, under the circular support, and the upper one secured to the support over the lower member, bearing balls disposed between the concentric members, and an annularly extending perforated ring disposed between the members to peripherally space the bearing balls, one of said concentric members having an annular groove in which the bearing balls may engage, and said perforated ring being provided with means for spacing itself from the other concentric member.

2. A refrigerator shelf comprising a stationary portion having a circular opening defined by a rigidly supported ring, parallel support bars extended as chords to the annular ring and secured at their ends to the ring, the said support bars being disposed below the plane of the shelf as a whole, an upwardly dished supporting plate secured rigidly to the support bars and having an annular peripheral ball race groove, a plate pivotally mounted on and above the supporting plate but spaced below the level of the upper surface of the shelf, bars secured across the upper surface of the upper plate and supported thereby flush with the upper surface of the shelf, a ring secured beneath the ends of the last named bars and supported thereby to rotate within the ring rigidly supported by the shelf, balls mounted in the ball race groove in the supporting plate to rotatably support the said upper plate, a perforated ring peripherally spacing the said balls and the said ring having upwardly pressed bosses for supporting the ring in spaced relation between the plates.

LYLE W. JOHNSON.
